B. C. SMITH,

FUEL FEEDING APPARATUS FOR INTERNAL COMBUSTION ENGINES

APPLICATION FILED JULY 8, 1916.

1,237,965.

Patented Aug. 21, 1917.

UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

FUEL-FEEDING APPARATUS FOR INTERNAL-COMBUSTION ENGINES.

1,237,965.

Specification of Letters Patent. Patented Aug. 21, 1917.

Application filed July 8, 1916. Serial No. 108,198.

To all whom it may concern:

Be it known that I, BENJAMIN C. SMITH, a citizen of the United States of America, residing at Bayonne, N. J., have invented a new and useful Fuel-Feeding Apparatus for Internal-Combustion Engines, of which the following is a specification.

My invention relates to improvements in oil burning engines of the high compression type, wherein fuel is injected into the engine cylinder at the desired period in the cycle of the engine. My object is to provide certain improved features of construction, particularly with relation to the operation 15 of the fuel valve, as used in combination with the other parts of the injecting mechanism.

Figure 1 is a vertical sectional view of the upper part of an engine cylinder, certain 20 parts which are associated therewith being shown conventionally.

Fig. 2 is a fragmentary view showing certain parts on a relatively enlarged scale and in a slightly different position from that indicated in Fig. 1.

It should be understood that the drawings are merely illustrative, and do not pretend to show exact proportions. Furthermore, the said drawings are illustrative of a preferred construction, it being my expectation that various changes and modifications may be made without departing from the spirit and scope of the invention.

In that form of the invention illustrated herein, 1 represents the upper part of an ordinary engine cylinder of the water jacketed type. 2 represents a working piston which is connected in the usual manner with the crank shaft, not shown. 3 represents the usual cylinder head, in this instance of the water jacketed type. 4 conventionally represents an air compressor which leads to a suitable air reservoir 5. 6 conventionally represents a fuel supply tank. 7 represents a fuel controlling means by which the quantity of fuel from tank 6 to the engine may be controlled, any suitable controlling means being employed. 8 represents a valve in the upper part of the engine cylinder past which fuel may be forced into the cylinder at the proper time. This valve is normally held closed by means of a spring 9. 10 is a fuel feeding piston in the form of a sleeve surrounding the stem of the valve 8. This pis-

ton sleeve is movable up and down in what I may term a plug 11, which is mounted in a bore in the cylinder head, and which may be held in place in any suitable manner, as by bolts 12-12. The piston sleeve 10 may have suitable packing rings 13. The fuel feeding piston 10 is moved up and down by the operation of the engine through the medium of any suitable means operating in time with the engine, the means shown being a walking beam or rocker arm 14 which is suitably connected with said piston 10 to move the same as the engine rocks said arm. 16 is an air pipe or passage leading from the compressor 4 through the receiver 5 to the plug 11, the inner end of said duct piercing the side of the bore in which the feeding piston 10 travels, the point of entry being slightly below the end of the piston 10 in its retracted position, so that at such time compressed air can enter the bore below the piston 10 and the seat for the valve 8. 18 is a fuel pipe or passage leading from the supply 6 through the controller 7 and into the plug 11, the inner end of said pipe 18 opening into the bore in which the piston 10 travels near to the seat for the valve 8. 20 is a suitable back check valve to prevent forcing the fuel back through the duct 18 when the fuel feeding piston 10 is advancing. This valve may, if desired, have a light 25 spring 22 to assist in closing the same at the proper time. The plug 11 has a gas tight fit in the piston head, one simple way for securing said fit being to taper the lower end of the plug and to provide a correspondingly tapered seat to receive the same. 21 represents an air inlet valve of any approved type, to admit air to the space in the working cylinder above the piston 2. The valve 8 in the form shown, has a tapered 25 lower end which takes into a correspondingly tapered seat in a contracted passage 24 at the lower end of the bore in the plug 10. This contracted passage 24 leads into the cylinder 1. The valve 8 is mechanically 30 opened at the proper time by one of the working parts of the engine, such as a cam, indicated conventionally at 25. This cam operates on a rocker arm 26 which is suitably connected with the stem of the valve 8 so that when the cam 25 is at the proper operative angle it will quickly unseat and open valve 8.

Operation: On the descent of the piston 2 the space within the working cylinder 1 is filled with air. On the ascent of the piston 2 this air is very highly compressed. When 5 the fuel feeding piston is retracted, fuel is fed in the proper quantity through the passage 18 into the space in the plug bore around the lower end of the valve 8. When the piston 10 is fully retracted, the compressed air passage is uncovered, and compressed air is forced into the bore of the plug in the space partially occupied by fuel. On the descent or forward movement of the fuel feeding piston 10 this air and fuel is compressed. At the proper moment, near the forward end of the feeding stroke, the cam 25 opens the valve 8, so that the then very highly compressed air and fuel in the bore around the stem of the valve 8 will be forced 20 into the combustion chamber of the working cylinder, the degree of compression being sufficiently greater than the degree of compression of the air in said working cylinder to cause the fuel to be forced thereinto. The 25 timing of the operation of these parts should, of course, be such that this feeding operation will occur at the proper moment in the cycle of the engine, and this may, of course, be varied by shifting the operative angle of 30 the cam 25 or in any other way well known to the mechanic skilled in this art.

In Fig. 1 it may be assumed that the piston 10 has reached, or has approximately reached, the forward end of its stroke in 35 which position the valve 8 is shown as open to admit fuel. In Fig. 2 the valve 8 is shown as closed and it may be assumed that the fuel feeding piston 10 is ascending, during which period fuel is being fed through the passage 40 18 past valve 20.

What I claim is:

1. In a fuel feeding apparatus for internal combustion engines, an engine driven fuel feeding piston, a mounting therefor having a bore in which said piston reciprocates, a fuel feeding passage arranged to lead from said bore to an engine cylinder, an outwardly opening valve for said passage, with means for normally holding the same closed, and 45 means for mechanically opening the same at certain times, a compressed air inlet in the mounting leading into said bore adjacent to the end of the fuel feeding piston at the back of its stroke, and a fuel feeding inlet into 50 said bore between said compressed air inlet and said valve.

2. In a fuel feeding apparatus for internal combustion engines, an engine driven fuel feeding piston, a mounting therefor 55 having a bore in which said piston reciprocates, a fuel feeding passage arranged to lead from said bore to an engine cylinder, an outwardly opening valve for said passage, with means for normally holding the same closed, and means for mechanically opening the 60

same at certain times, a compressed air inlet in the mounting leading into said bore adjacent to the end of the fuel feeding piston at the back of its stroke, and a fuel feeding inlet into said bore between said compressed air inlet and said valve, the means for opening 70 said valve comprising a cam.

3. In a fuel feeding apparatus for internal combustion engines, an engine driven fuel feeding piston, a mounting therefor 75 having a bore in which said piston reciprocates, a contracted fuel feeding passage arranged to lead from said bore to an engine cylinder, means for supplying fuel and air to said bore on the back stroke of the piston 80 to be compressed on the forward stroke thereof, a valve for said contracted passage and means in addition to the aforesaid parts for opening said valve at the proper time near the end of the fuel feeding stroke 85 of said piston, to permit said compressed air and fuel to be forced through said fuel feeding passage.

4. In a fuel feeding apparatus for internal combustion engines, an engine driven 90 fuel feeding piston, a mounting therefor having a bore in which said piston reciprocates, a fuel feeding passage arranged to lead from said bore to an engine cylinder, a valve for said passage with means for 95 closing the same, a compressed air inlet in said mounting leading into said bore adjacent to the end of the fuel feeding piston at the back of its stroke, a fuel feeding inlet into said bore between said compressed 100 air inlet and said valve.

5. In a fuel feeding apparatus for internal combustion engines, an engine driven fuel feeding piston, a mounting therefor having a bore in which said piston reciprocates, a fuel feeding passage arranged to lead from said bore to an engine cylinder, a valve for said passage with means for closing the same, a compressed air inlet in 110 said mounting leading into said bore adjacent to the end of the fuel feeding piston at the back of its stroke, a fuel feeding inlet into said bore between said compressed air inlet and said valve, with means for forcing compressed air into said bore 115 through said air inlet when the fuel feeding piston is at the back of its stroke.

6. In a fuel feeding apparatus for internal combustion engines, an engine driven fuel feeding piston, a mounting therefor 120 having a bore in which said piston reciprocates, a fuel feeding passage arranged to lead from said bore to an engine cylinder, a valve for said passage with means for closing the same, a compressed air inlet in 125 said mounting leading into said bore adjacent to the end of the fuel feeding piston at the back of its stroke, a fuel feeding inlet into said bore between said compressed air inlet and said valve, with means for feeding 130

fuel through the fuel inlet into said bore while said fuel feeding piston is retracted.

7. In a fuel feeding apparatus for internal combustion engines, an engine driven fuel feeding piston, a mounting therefor having a bore in which said piston reciprocates, a fuel feeding passage leading from

said bore to an engine cylinder, a valve for said passage, a compressed air inlet in said mounting leading into said bore to supply 10 air thereto, and a separate fuel feeding inlet leading into said bore to supply fuel thereto.

BENJAMIN C. SMITH.
